James Eaton, of Mount Island, Va.
Letters Patent.

The schedule referred to in these Letters Patent, making part of the same containing a description in the words of the said James Eaton himself, of his improvement in the construction of bedsteads. —

Is it known that James Eaton of Mount Island, in the County of Fauquier & State of Virginia have invented a new & useful improvement in the construction of bedsteads, by which the ticking bottom or cords may be strained and curtains created upon low post bedsteads, with facility & strength, that the following is a full & exact description of the construction & operation of the said improvement as invented by me, reference being had to the annexed drawings. — —

These bedsteads are made in the ordinary manner of the common low post bedstead, with the exception that one of the rails marked a is constructed on the rotary principle, is round or many sides with a strong metallic or wood quidgion b, inserted into each end of this rail, penetrating longitudinally, about six inches. The part of the quidgion inserted in the rail should be made square & from half an inch to an inch thick. —

The other or projecting part should be perfectly round & of nearly the same diameter with the square end, its diameter to be reduced at the outward end an inch in length on which a male screw should be cut & a round tap nicely adjusted on the outside of which tap there should be cut a deep depression in the usual manner to receive the end of the screw driven, hereafter to be described, for the purpose of taking off this tap at pleasure. —

The whole length of this round projecting part of the quidgion should be adapted to the thickness of the posts or upright pieces of the bedstead into which it is to be let in a round opening which is to be made thro' the post with a cavity or depression of greater diameter on the outside to admit the tap. If the posts at the joining of the rails, should be five inches square, then the length of the round part of the quidgion should be four inches & those four inches long. The quidgion, or round tenon, may be cut on the end of the running rail with a male screw cut at the end thereof with a tap to secure it, or it may be made to turn in the post secured by a common male screw inserted into a female screw in the end of the tenon. — A ring wheel c of four or six inches in diameter is fitted on one end of the round rail in such a manner as to embrace the square part of the quidgion, which in this end of the rail is allowed to project an eighth of an inch from the wood for that purpose;

The circumference of which wheel is cut into notches or teeth like all rag wheels, so that with a pull, hatched or trigger d, with one end dropped into one of these notches, the other end fastened to the bed post by a strong screw or round pin, passing thro' or round hole in this end of the pull, into the post. & the whole so arranged that the rail is allowed to revolve from above outwards, & that its motion cannot be reversed without raising the loose end of the pull out of the notch of the rag wheel. Between the rag wheel & the post is a washer or ring made to fit the round part of the pulley, which may be embedded a little into the wood of the post but projecting from it so far as to prevent the rag wheel from cutting the post, & to let the trigger have more room to play on the wheel. This revolving rail may also be braced to prevent it from splitting if necessary. The packing bottom e, is attached to the side rails or to the revolving rail, & to the one opposite to it by eye-hilt holes which button on knobs in the side rails, as in the common bedstead: & is attached to the two end rails by means of a rope which passes thro' the hem of the packing on each side (to strengthen the hole) its ends passing thro' loops sewed on the ends of the packing & over knobs in the end rails; the end of which being tied together on each side, so that when the revolving rail is turned by a lever the end ropes are stretched at the same time that the canvas is strained from side to side which will tighten in every direction. The curtain frame f, is sustained by four braces g, g, h, h, made of strong wire, one end of which is inserted into a small hole in the top of each post, the other divides in such a manner that one branch or brace reaches to the corner of the curtain frame whilst the other extends the distance of a foot from the corner ...

These upper ends of the braces must have shoulders i, with bolts k, extending therefrom in which the frame rests secured by screw taps l, or by broad heads on the bolts with washers m, n, slipped on them so as to embrace the bolts under the heads in the manner represented in the drawings. This bedstead can be taken down by a screw driver screw such as is represented in the drawings at the letter n ...

That I claim as my invention which to secure by Letters patent is the before described improvement in the construction of bedsteads, by which the packing bottom can be strained with a single revolving rail & the curtain frame sustained by the iron braces ...

In testimony whereof I have hereunto subscribed my name before two witnesses at the City of Washington this 17th day of December 1833 —
